UNITED STATES PATENT OFFICE

163,939

AWNNG OR SIMILAR ARTICLE

Nicholas L. Etten, Cedar Falls, Iowa

Application April 19, 1951, Serial No. 14,890

Term of patent 14 years

(Cl. D21--1)

To all whom it may concern:

Be it known that I, Nicholas L. Etten, a citizen of the United States, and a resident of the city of Cedar Falls, in the county of Black Hawk and State of Iowa, have invented a new, original, and ornamental Design for an Awning or Similar Article, of which the following is a specification, reference being had to the accompanying drawing, forming a part thereof.

On the drawing:

Figure 1 is a front perspective view of an awning or similar article, showing my new design, showing the front and one side of the awning; and

Figure 2 is a similar front perspective view of the awning or similar article, showing the front and other side.

The dotted line showings in both figures of the drawing are for illustrative purposes only.

I claim:

The ornamental design for an awning or similar article, substantially as shown and described.

NICHOLAS L. ETSEN.
